COLUMBIA PLANOGRAPH CO., WASHINGTON, D. C.

UNITED STATES PATENT OFFICE.

CHARLES W. LINSCOTT, OF SAN FRANCISCO, CALIFORNIA.

STEERING DEVICE.

1,160,296.

Specification of Letters Patent. Patented Nov. 16, 1915.

Application filed May 5, 1915. Serial No. 26,028.

To all whom it may concern:

Be it known that I, CHARLES W. LINSCOTT, a citizen of the United States, residing at San Francisco, in the county of San Francisco and State of California, have invented certain new and useful Improvements in Steering Devices, of which the following is a specification, reference being had to the accompanying drawings.

10 This invention relates to an improved steering device and has for one of its objects to provide an improved rudder construction and mounting which will permit of the easy and quick removal of the rudder when broken, and the arrangement of a new 15 rudder in position without delaying the progress of the vessel.

The invention has for another object to provide an improved construction and 20 mounting of the rudder post, and a sectional rudder adapted to be assembled and mounted for turning movement upon the post from the deck of the vessel.

It is a further object of my invention to 25 provide an improved auxiliary rudder which will enable the vessel to be very quickly turned in cases of emergency.

The invention has for a further object to 30 provide a rotary rudder or steering propeller applicable to either steam or sailing vessels and which may be mounted in multiples of any desired number beneath the bow or stern of the vessel.

With the above and other objects in view, 35 my invention consists in the novel features of construction, combination, and arrangement of parts to be hereinafter more fully described, claimed, and illustrated in the accompanying drawings, in which,

40 Figure 1 is a side elevation of a portion of a vessel provided with my improved rudder mounting and auxiliary rotary steering device; Fig. 2 is an enlarged vertical section of the rudder mounting; Fig. 3 is a section 45 taken on the line 3—3 of Fig. 1; Fig. 4 is a section taken on the line 4—4 of Fig. 2; Fig. 5 is a section taken on the line 5—5 of Fig. 1; Fig. 6 is a vertical section similar to Fig. 2, illustrating a slightly modified construction of the rudder; Fig. 7 is a top plan view of the modified form; and Fig. 8 is a section taken on the line 8—8 of Fig. 6.

It is to be understood that the accompanying 50 illustrations, disclosing the mounting and arrangement of the steering devices, are

illustrative only, and that the practical application of the invention forming the subject-matter of this application is not restricted to any particular type of vessel or construction thereof.

60 In the drawings I have shown the stern portion 5 of a steam vessel, of the double or quadruple screw-propeller type, and 6 designates one of the screw-propellers which may be of any approved construction. The 65 keel 7 of the vessel extends rearwardly beneath the propeller and constitutes a seat or support for the lower end of the rudder post, to be hereinafter referred to. The vessel 5 is provided above and rearwardly of 70 the propeller 6, with a well or compartment 8, the upper end of which is closed by removable deck planks 9. Removable bottom plates 10 are normally supported by ledges or shoulders 11 which constitute the base 75 wall of the well or compartment. These plates are held in place by removable cleats or bars 12.

Through the well 8, the vertically disposed obliquely inclined rudder post 13 extends, the deck planks 9 and the bottom plates 10 of the well having their opposed edges recessed to accommodate said rudder post. The upper and lower ends of this post are provided with circular head plates 80 14, the lower plate being securely bolted, as at 15, to the keel 7 of the vessel, while the upper head plate 14 is similarly bolted to a longitudinally extending beam 16. The upper end portion of this post 13 is of relatively small diameter, as shown at 17, and from a point within the well 8 to the lower end of the rudder post, the same is of increased diameter.

85 The rudder proper includes a tubular upper end portion 18 which is constructed in two sections adapted to embrace the reduced upper end portion 17 of the rudder post. These semi-circular sections are tightly clamped or secured together by 90 means of bolts or other suitable fastening devices, and to the lower end of this upper portion of the rudder, a collar 19 is securely fixed by means of clamping or set screws 20. The lower ends of the sections 95 of the portion 18 of the rudder extend through the recesses in the edges of the deck planks 9 and are outwardly flared, as indicated at 21, and provided with collar sections 22 which are adapted to be securely 100 105 110

bolted to the split collar 23 formed upon the upper end of the body of the rudder, indicated at 24.

25 designates a pair of brace bars which extend across the deck planks 9 and are removably secured at their ends to the deck of the vessel. The opposed edges of these brace bars are notched or recessed to receive the upper portion 18 of the rudder, 10 and the upper faces of these brace bars and the opposed lower face of the collar 19 are provided with raceways to receive the anti-friction balls 26, whereby friction is reduced to a minimum in the turning movement of the rudder.

In the illustrated embodiment of my invention, I have shown the body 24 of the rudder provided with a longitudinally extending rib or fin 27. The opposite side of this body is longitudinally split, as indicated at 28, and between these spaced portions of the body, the rudder blade 29 is adapted to be fitted. This blade may be either of wood or metal and is securely fixed in place by means of a plurality of bolts or rivets 30. These bolts or rivets are preferably cut by means of an acetylene torch when it is desired to remove the rudder blade. At the lower end of the body 30 24 of the rudder, the same is formed with a circular plate or disk 31 and between these opposed faces of this disk and the head 14 on the lower end of the rudder post, suitable bearing balls or rollers are arranged. The 35 longitudinal rib or fin 27 of the body of the balanced rudder and the blade 29 are provided with openings 32 for a purpose to be presently explained.

Upon the beam 16, a suitable track 33 is secured, upon which chain hoist sheaves 34 are mounted to travel. If the rudder should be so badly injured that the vessel cannot be properly steered, the said rudder may be removed and another rudder carried by the 45 vessel arranged in its place in the following manner. The brace bars 25 and the deck planks 9 are first removed and the collars 22 and 23 then disconnected so that the upper portion 18 of the rudder proper may 50 be removed from the post 17. The chain hoist is connected to the lower body section of the rudder and the plates 10, constituting the bottom wall of the well, together with the retaining bars 12, are then removed 55 and placed upon the deck of the vessel. Any desired power may be used to operate the chain hoist so that the body of the propeller is then lifted or elevated upon the post 13. After removing the blade 29 from 60 the body of the rudder, the split side thereof will spread apart so as to permit of the removal of this body from the reduced upper end portion of the post 17, which is of slightly greater diameter than the space 65 between the opposed side plates of the rudder.

der body. The new rudder is applied by first engaging the body section thereof upon the reduced upper end portion of the post 17 and then securing the blade 29 thereto. During this operation, an iron bar may be 70 passed through the openings 32 in the longitudinal balancing rib 27 and the blade 29 of the rudder body so as to support the rudder in place and thus avoid possibility of the same accidentally moving down upon the 75 rudder post and breaking the keel plate 7.

In Figs. 6, 7 and 8 of the drawings, I have illustrated a slightly different form of the rudder which is especially designed for use upon large vessels. In this construction, 80 the mounting of the rudder is substantially identical with that above referred to, the only difference being that the rudder blade is constructed in two separate sections 35 which are fitted into grooves or channels 85 36 provided in the body casing of the rudder and riveted or bolted thereto, as indicated at 37. In this form of the invention, I have also shown the upper end of the rudder post provided with a heavy integral bracing arm 90 38 which is bolted or otherwise rigidly secured, as at 39, to a part of the vessel structure. In both of the rudder constructions above referred to, it will be seen that I have produced a very simple and durable mounting which will permit of the free turning movement of the rudder in order to properly steer the vessel and while, at the same time, the rudder will withstand the pressure and 95 strong currents, it is not liable to be easily broken. In the event, however, that the rudder should be broken, the same may be easily and quickly removed and replaced by a new rudder in the manner described.

In order to supplement the action of the 105 rudder above described and to quicken the turning movement of the vessel, I provide an auxiliary steering device. This steering device, when employed upon a single screw steamer, is preferably located under the 110 fore-foot or the bow of the vessel's hull; but for large, high-speed vessels having twin or quadruple propelling screws, the auxiliary steering device is preferably installed in the "skeg" or "deadwood" forwardly of the propelling screws and the rudder, and at such point as will not interfere therewith, as clearly shown in Fig. 1. Provision is made in the "skeg" immediately above the keelson 115 of the vessel, for a metal casting 40 which is securely fixed in place by means of the vertical bolts 41 passing through the ends of the casting, the keelson, and the keel. The central portion of the casting 40 is cut out or recessed, as at 42, and the keelson is also recessed, as shown at 43. These opposed recesses accommodate the rotary steering member which consists of a series of propeller-shaped blades 44 connected together by an annular metal band or rim 45 which 120

is shrunk and permanently secured upon said blades. The rim or band is provided upon one face with gear teeth, as shown at 46, and with the same, the driving gear 47, fixed upon the lower end of a vertical shaft 48, is engaged. Horizontal straps or bars 49 are secured to opposite sides of the casting 40 and extend across the recess 42, and in these straps, the ends of the shaft 50 of the rotary steering member, are journaled.

10 A well casing 51 is built in the hull of the vessel and extends below the deck thereof. This casing provides a protecting housing for the shaft 48. Upon the shaft 48, adjacent its lower end, a collar 52 is fixed, and the bearing block 53 is disposed in the lower end of the casing 51 and seated upon the casting 42, said bearing block having lugs for interlocking engagement in recesses provided in the casting. The casting 42 is further provided with an opening shown at 54, which is slightly greater in diameter than the diameter of the pinion 47, so that the shaft may be lifted from the well, when desired. Between the collar 52 and the bearing member 53, rollers or bearing balls may be arranged. A cap 55 is secured upon the upper end of the well or casing 51 and upon the upper end of the shaft 48, projecting above this cap, the gear 56 is fixed, anti-friction bearing members being arranged between the face of said gear and the opposed face of the cap 55.

15 57 designates a second longitudinally disposed track suitably mounted above the deck of the vessel and upon which the sheave block, indicated at 58, is engaged. A hoist chain, which is trained over the sheave, is adapted to be connected to the upper end 20 of the shaft 58, whereby the same may be readily removed through the well 51 or replaced in operative position. It is, of course, obvious that, in place of the gearing above described, a miter or beveled gear or a worm 25 drive gear may be employed. The power gear, shown at 59, which meshes with the gear 56, may be driven from a gas engine, electric motor, or any other suitable source of power. It is also to be borne in mind 30 that, while I have shown only one of the rotary steering devices, the same may be employed in multiples of two or more. By the provision of this rotating steering member, the action of the rudder is supplemented so that the vessel may be quickly 35 turned, and liability of collision with another vessel thus avoided. It will, therefore, be appreciated that the present invention is in the nature of a life-saving appliance for vessels as it, to a great extent, obviates probable loss of life due to shipwreck 40 or collision. The rotation of the steering member may be readily reversed by the proper manipulation of a suitable lever 45 under the control of the operator, so as to

turn of steer the vessel in the desired direction.

From the foregoing description, taken in connection with the accompanying drawings, the construction, manner of operation, 70 and several advantages of my invention will be clearly and fully understood. It will be understood that, owing to the particular manner of mounting both the rudder and the rotary steering device, the same are, to 75 a great extent, protected against injury without, to a material degree, lessening their effectiveness in operation.

The invention, as a whole, is also comparatively simple in its construction and 80 may be embodied in the construction of various types of vessels without greatly increasing the cost thereof. Owing to the easy accessibility of the several parts of the invention, the same may be readily removed 85 or replaced in operative position with a minimum of manual labor and expedition in cases of emergency.

While I have shown and described the preferred construction and arrangement of 90 the several elements employed, it is to be understood that the invention is susceptible of considerable modification therein, and I, therefore, reserve the privilege of resorting to all such legitimate changes as may be 95 fairly embodied within the spirit and scope of the invention as claimed.

Having thus fully described my invention, what I desire to claim and secure by Letters Patent is:—

1. A steering rudder for vessels including in combination with a fixed rudder post, the rudder proper having a body mounted for turning movement upon the post, a rudder blade, said body being provided with means 105 whereby the blade may be detachably connected to said body, said means, when the blade is detached from the body, enabling the body of the rudder to be moved laterally with respect to the post to engage the body 110 thereon or remove the same.

2. A steering rudder for vessels including in combination with a fixed rudder post having a reduced upper end portion, a rudder provided with a longitudinally split body 115 mounted to rotate upon said post, a rudder blade adapted to be detachably secured in the split side of the body, said body being adapted to be raised upon the post and the rudder blade removed therefrom and the 120 body forced laterally off of the reduced upper end of the rudder post.

3. A steering rudder for vessels comprising in combination with the permanently mounted rudder post, the rudder proper 125 mounted for turning movement on said post and consisting of a lower body portion and an upper portion including two separable sections embracing said post and removably connected to said body portion, said body 130

portion, when the sections are disconnected therefrom, being adapted to be raised upon the post to an inoperative position.

4. A steering rudder for vessels including in combination with a permanently mounted rudder post having a reduced upper end portion, the rudder proper mounted for turning movement on said post and consisting of a lower body portion and an upper portion including two sections adapted to embrace the upper portion of the post and removably connected to the body portion of the rudder, said body portion being longitudinally split whereby the same may be engaged upon the upper reduced portion of the post or removed therefrom, and a rudder blade secured between the split portions of the rudder body.
5. The combination with a vessel having a chamber in the hull portion thereof and removable top and bottom closures for said chamber, of an obliquely inclined permanently mounted rudder post extending

through said chamber having a reduced upper end portion, a rudder consisting of a longitudinal split body portion having an extended reduced neck disposed within said chamber when the rudder is in operative position, semi-tubular rudder sections adapted to embrace the upper reduced portion of the post and detachably connected to the upper end of said neck within said chamber, a rudder blade fixed between the opposed split portions of the rudder body, said semi-tubular sections of the rudder being adapted to be removed and the body section elevated upon the post whereby the same may be removed from the post after the removal of the rudder blade.

In testimony whereof I hereunto affix my signature in the presence of two witnesses.

CHARLES W. LINSCOTT.
